UNITED STATES PATENT AND TRADEMARK OFFICE
CERTIFICATE OF CORRECTION

PATENT NO. : Des. 566,678 S
APPLICATION NO. : 29/286639
DATED : April 15, 2008
INVENTOR(S) : Henrik Jensfelt

Page 1 of 1

It is certified that error appears in the above-identified patent and that said Letters Patent is hereby corrected as shown below:

Title page item (73), "Sony Ericsson Mobile Communications AB" should read
-- Sony Ericsson Mobile Communications AB --.

Signed and Sealed this
